Application March 23, 1939, Serial No. 263,656
In France April 1, 1938

4 Claims. (Cl. 62—122)

This invention relates to the handling of liquefied gases and particularly to an apparatus adapted to facilitate the withdrawal of liquid from an apparatus in which such liquid is produced by liquefaction and rectification of gaseous mixtures and the transference of the liquid to vessels for storage and transportation.

In the method of producing liquefied gases by liquefaction and rectification of gaseous mixtures, 10 a liquid consisting of one of the constituents of the gaseous mixture may be accumulated in the rectification column. It is frequently desirable to withdraw such a liquid product and to deliver it to vessels for transportation. In commercial 15 operations, large volumes of such liquids are accumulated and transported in suitably insulated containers on trucks, railway cars, etc.

In the production of liquefied gases it is desirable that the liquefied gas in the liquefying apparatus be kept therein under as low a pressure 20 as possible so that as the liquid in the apparatus is withdrawn the resultant pressure-drop will be reduced to a minimum and less vaporization of the liquid remaining in the apparatus will take 25 place.

Liquefied gas withdrawn from the liquefying apparatus commonly is collected in heat-insulated storage vessels from which it is transferred to smaller vessels mounted on railway cars, trucks, 30 or the like, for transportation to the place of use. Such transfer may be obtained by gravity, by maintaining the liquefying apparatus and storage vessel at an elevation higher than the transportable vessels to be filled from the storage 35 vessel, but such an installation is impractical due to the height which it would be necessary to maintain the liquefying apparatus and storage vessel. A special pump for liquefied gases may be used for transferring the liquefied gas from one vessel

40 to another, but in many instances it is more advantageous to obtain automatically such a transfer of the liquefied gases by means of gaseous pressure exerted above the liquefied gas in the storage or other vessel to be emptied. However, 45 such transference of the liquefied gas seldom can be carried out when the storage vessel is connected to the rectifying apparatus as the pressure created above the liquid in the storage vessel practically prevents the liquefied gas from flowing 50 from the liquefying apparatus to the storage vessel, and such stopping of the flow of the liquefied gas from the liquefying apparatus entails an undesirable disturbance of the liquefying operation.

55 The patent to Lagarde No. 1,998,629 discloses

an apparatus which overcomes the above disadvantages in that the liquefied gas is conducted from the liquefying apparatus to a first vessel having a valve through which the liquid may pass to a second vessel from which, after the closing 5 of the valve in the first vessel, it may be discharged under pressure while the first vessel simultaneously is being filled under a low pressure with liquefied gas from the liquefying apparatus.

It is an object of the present invention to provide an apparatus which has the advantages of the apparatus disclosed in the aforesaid Lagarde patent, and which has further advantages resulting from the simplification of the procedure and 15 apparatus.

In accordance with the present invention a receptacle generally corresponding to one of the receptacles utilized in the aforesaid patent is embodied in the liquefaction column, and preferably located about the heat exchange tubes in the vaporizing section thereof. Thus the present invention results not only in simplifying the structure, but also in having the further advantage that it provides for maintaining a reserve 25 supply of liquefied gas within the vaporizing section of the liquefaction column which will facilitate the starting of a column after it has temporarily been shut down.

Other objects and advantages of the invention 30 will be apparent as it is better understood by reference to the following specification and the accompanying drawing, which illustrates diagrammatically a portion of a liquefaction column embodying my improvements, together with the 35 auxiliary equipment which is utilized therewith to facilitate the transfer of the liquefied gas from the column without disturbing the operation thereof.

In describing the invention, I shall refer to the 40 production of liquefied oxygen as an example, although the invention may be utilized in a similar manner to transfer other liquefied gases from the source thereof to containers for storage or transportation. Thus, any liquefied gas which is 45 produced and accumulated in a manner similar to the operation of a liquefaction column for the separation of the elements of atmospheric air may be treated similarly in the transfer of the liquid from the source.

Referring to the drawing, 5 indicates the shell 50 of a conventional liquefaction column of which I have illustrated only that portion ordinarily known as the vaporizer, in which liquid oxygen, for example, accumulates as the result of recti- 55

fication of liquids and gases in the upper portion of the column (not shown). It will be understood that the shell 5 is insulated in the usual manner to avoid, as far as possible, heat losses which are incidental to the operation of such a column. The accumulated liquid oxygen is delivered from the upper part of the column through a pipe 6 and accumulates in the space surrounding a plurality of tubes 7, communicating with the lower section of the column 8. Through these tubes, vapors rising from the lower section of the column travel upwardly to a head 9 and are condensed by heat exchange with the liquid oxygen surrounding the tubes. The vapors consist principally of nitrogen and are liquefied, the liquid flowing backwardly to be received by collectors 10 or to pass again into the lower section of the column. The liquid nitrogen may be withdrawn through a pipe 11 and utilized in the usual manner as reflux liquid at the top of the column.

In accordance with the present invention, I provide a cylindrical wall 12 surrounding the space in which the liquid oxygen is accumulated, affording a dam over which a quantity of liquid oxygen corresponding to the output of the air separation apparatus uninterruptedly flows into the annular space between the wall 12 and the shell 5. This liquid oxygen is transferred from this space as will be explained hereinafter, while a sufficient body of liquid oxygen is maintained about the tubes 7 to perform its function of condensing nitrogen in the tubes.

To effect the transfer of the liquid oxygen, I provide a receptacle 13 which may be of any suitable form, though preferably spherical, enclosed within a suitable housing 14 with heat insulating material between in quantity sufficient to minimize heat losses. A pipe 15 connects the annular space into which the liquid oxygen overflows to the top of the receptacle 13, said pipe being provided with a valve 16.

A pipe 17 is connected to the receptacle 13 and is provided with a valve 18. Vapors which are formed incidentally by evaporation of liquid in the receptacle 13 escape through the pipe 17 while the valve 18 is open. A pipe 19 is similarly connected to the receptacle 13 and is provided with branches 20 and 21, respectively having valves 22 and 23. The pipe 21 is connected to a source of gas under pressure which may be introduced through the pipe 19 to the interior of the receptacle 13. The pipe 20 permits the withdrawal of gases and vapors from the receptacle 13, after the liquid has been expelled therefrom in the manner hereinafter described. A pipe 24 is connected to the bottom of the receptacle 13, and is provided with a valve 25. The pipe 24 may be provided with a suitable connection (not shown), permitting the delivery of liquid to any suitable transportation or storage vessel. Both the pipes 15 and 25 are surrounded by casings 26 and 27, enclosing insulating material to avoid heat losses.

In the operation of the device as described, assuming that the receptacle 13 is empty and is to be filled with liquid oxygen, the valve 16 is opened. At the outset the annular space between the shell 5 and the wall 12 contains liquid oxygen, which flows into the receptacle 13. When all the liquid oxygen contained in this annular space above the level of the pipe 15 has been discharged, there only flows into the receptacle a quantity of liquid oxygen corresponding to the output of the liquefaction column. The valve 18 is opened at the same time as the valve 16 to permit the discharge

of incidental vapors from the receptacle. When sufficient liquid has accumulated in the receptacle 13, the valves 16 and 18 are closed, the valve 25 is opened, the pipe 24 being then connected to a receiving vessel, and the valve 23 is opened to permit the introduction of a suitable gas under pressure which forces the liquid from the receptacle 13 through the pipe 24 into the receiving vessel. The annular space between the shell 5 and the wall 12 is filling meanwhile, without any change occurring in the level of the liquid bath surrounding the tubes 7. When the receptacle 13 is empty, the valves 23 and 25 are closed, the valves 16 and 18 are reopened and the cycle is repeated.

From the foregoing it will be apparent that the present invention not only provides a simpler apparatus for obtaining the advantages of the apparatus of the aforesaid Lagarde patent, but that it also provides for the maintaining of a reserve supply of liquid about the tubes 7 before stopping the operation of the liquefaction column, thus facilitating the starting of the column after it has been temporarily shut down. Without this provision, the column would be drained of its reserve liquid and it would be necessary to accumulate liquid in the column to condense the nitrogen therein before the proper functioning of the rectification apparatus could be established. This and other advantages facilitate the commercial application of the method and apparatus and ensure a more economical operation in respect to the transfer of liquid from the column to vessels for transportation and storage.

Various changes may be made in the form and arrangement of the structure and in the details of operation, without departing from the invention or sacrificing the advantages thereof.

I claim:

1. In a plant for recovering in the liquid state a constituent of a low-boiling gaseous mixture, a separation section in which the liquid constituent is formed, a vaporising section which receives the liquid constituent from the separation section and in which a portion of said constituent is revaporised and from which the remaining liquid constituent may stream by overflow, a storage section for receiving such overflowing liquid constituent, a receptacle adapted to receive the liquid constituent; means for connecting said storage section with said receptacle, means for interrupting said connection; and means for introducing a gas under pressure above the level of the liquid in the receptacle to act on the liquid constituent therein to discharge said liquid constituent from the receptacle.

2. In a plant for recovering in a liquid state a constituent of a gaseous mixture, a liquefaction column having a vaporizing section, tubes in said vaporizing section through which gas to be cooled is adapted to pass, a liquefied-gas storage receptacle surrounding at least a portion of said tubes and adapted to maintain a predetermined level of liquid about said tubes, a compartment in said vaporizing section of the column adapted to receive liquefied gas from said storage receptacle, a storage vessel exterior of said column, a passage connecting said exterior storage vessel with said compartment, and means for discharging liquefied gas from said exterior storage vessel.

3. In a plant for recovering in a liquid state a constituent of a gaseous mixture, a liquefaction column having a vaporizing section positioned to receive liquefied gas from a rectification section, tubes in said vaporizing section through

- which gas to be cooled is adapted to pass, a wall spaced from the inside of the liquefaction column and surrounding said tubes, said wall forming a receptacle about said tubes for receiving the liquid constituent from the rectification section of said column to act as a heat exchange medium to cool gases passing through said tubes, said wall also cooperating with the surrounding wall of the liquefaction column to define a space for receiving liquefied gas from the receptacle about said tubes, a storage vessel exterior of said column, a passage connecting said storage vessel with the space between the wall of the liquefaction column and the wall surrounding said tubes in the vaporizing section thereof, and means for discharging liquid from said storage vessel.
4. In a plant for recovering in a liquid state a constituent of a gaseous mixture, a liquefaction column having a vaporizing section positioned to receive liquefied gas from a rectification section, tubes in said vaporizing section through which gas to be cooled is adapted to pass, a wall spaced
- 5 from the inside of the liquefaction column and surrounding said tubes, said wall forming a receptacle about said tubes for receiving the liquid constituent from the rectification section of said column to act as a heat exchange medium to cool gases passing through said tubes, said wall also cooperating with the surrounding wall of the liquefaction column to define a space for receiving liquefied gas from the receptacle about said tubes, a storage vessel exterior of said column, a 10 passage connecting said storage vessel with the space between the wall of the liquefaction column and the wall surrounding said tubes in the vaporizing section thereof, a valve for interrupting the flow of liquid through said passage, means for introducing a gas under pressure above the level of the liquid in said exterior storage vessel, and means for withdrawing a liquid from said exterior receptacle simultaneously with the introduction of a gas under pressure above the level 15 thereof.
- 20

HENRI BONNAUD.
